UNITED STATES PATENT OFFICE

FREDERICK LINDMEIER AND JUSTUS LINDMEIER, OF OAK PARK, ILLINOIS.

HUMIDIFIER.

1,273,888.

Specification of Letters Patent.

Patented July 30, 1918.

Application filed February 11, 1918. Serial No. 216,459.

To all whom it may concern:

Be it known that we, FREDERICK LINDMEIER and JUSTUS LINDMEIER, citizens of the United States, residing at 735 North 5 Grove Ave., Oak Park, in the county of Cook and State of Illinois, and 819 Woodbine Ave., Oak Park, in the county of Cook and State of Illinois, respectively, have invented a certain new and useful Improvement 10 in Humidifiers, of which the following is a full, clear, concise, and exact description, reference being had to the accompanying drawings, forming a part of this specification.

15 Our invention relates to a humidifier constructed within either a steam or hot water radiator. The object of the invention is to provide wicks from which moisture supplied thereto will be evaporated by the air which is heated in the radiator itself. A further object of the invention is to provide means for applying moisture to the wick near the top thereof so that gravity will assist in carrying the moisture to the extremity of 20 the wick. A further object of our invention is to provide a drip pan which is integral with the radiator and so positioned that if the radiator cools off while the moisture supplying means for the wick continues its 25 operation the drip from the wick will be prevented from falling upon the floor and will be later evaporated when heat is again applied to the radiator.

30 Our invention is illustrated in the accompanying drawings in which:

Figure 1 is an elevation of a radiator containing a humidifier of our invention, part of the radiator being broken away;

Fig. 2 is a section on the line 2-2 of Fig. 40 1; and

Fig. 3 is a section on the line 3-3 of Fig. 1.

Similar characters of reference refer to 45 similar parts throughout the several views.

Our invention is an improvement upon the humidifier shown in our Patent No. 1,249,432 and upon the humidifier of our application Serial No. 203,490, filed February 23, 1917.

50 Although not herein illustrated it is to be understood that the control apparatus illustrated in our said co-pending application may be used with the humidifier of our present invention.

55 The radiator to which our invention is applied is made up of a plurality of sec-

tions 4, some of which may be of usual and unmodified construction while others of which, such as 5, 6, 7, and 8, are modified to form when the radiator sections are clamped together an upper tank or chamber 9 and a 60 lower tank or chamber 10. The intermediate sections, such as 6 and 7, are provided with "U" shaped flanges 12 carried by the center columns 13 and adapted to be brought into abutment with the corresponding 65 flanges of adjacent radiator sections. The sections 5 and 8 are provided with flanges 14 for registration with the flanges 12 and also with inclosing end plates 15 which form when the sections are clamped together the 70 ends of the upper chamber or reservoir. The lower chamber or reservoir 10 is formed by registering flanges 16 on sections 6 and 7 and by flanges 17 and end plates 18 on sections 5 and 8. By this construction the 75 lower or drip reservoir is made about two inches wider than the upper reservoir so that any water which overflows the upper reservoir will be caught in the lower. A pair of wicks 20 are hung over the side walls 80 of the upper reservoir, the inner ends extending to a point near the base of the upper reservoir and the outer ends hanging a suitable distance over the sides and between the middle and outer columns of the radiator. 85

In the operation of our invention water is placed in the upper reservoir either automatically, as described in our co-pending application above referred to, or by hand. The portions of the wicks 20 hanging over the outside of the upper reservoir are kept wet from the water within the reservoir and since these wicks are suspended near the top of the radiator they are passed by a current of air which has already been heated 90 from the lower portions of the radiator. By this arrangement a great deal more water may be evaporated than would be possible with wicks taking on their moisture at the bottom instead of at the top. The wicks 20 95 may be made of such length that in the ordinary operation of the device the water will be evaporated at such a rate as to prevent dripping from the lower edge of the wick into the lower receptacle 10, but upon the 100 cooling off of the radiator, as for example when the valve 22 is closed, the water continues to be absorbed by the wicks 20 and accumulates at the lower edges thereof in such quantities that it drips into the lower 105 110

- receptacle 10. When the heat is again turned on the water which has accumulated in the lower receptacle evaporates, though provision may be made for drawing it off if desired.
- 5 We have found linen cloth to be most satisfactory for use as wicks and have found it convenient to pass wires 23 through hems in the cloth, though other obvious means may be used for retaining the inner ends of 10 the wick beneath the liquid in the upper reservoir.
- Having thus described our invention what we claim as new and desire to secure by Letters Patent of the United States is:
- 15 1. A combined radiator and humidifier comprising a plurality of vertically arranged radiator sections, each section including a plurality of spaced heating conduits, coöperating flanges on certain of said sections forming upper and lower water receiving reservoirs, and absorbent material for conducting water from the upper receptacle, a portion of said absorbent material 20 extending over said lower receptacle, the lower reservoir being wider than the upper.
2. A combined radiator and humidifier comprising a plurality of vertically arranged radiator sections, each section including a plurality of spaced heating conduits, upper and lower base and side flanges forming part of certain of said sections and arranged to coöperate with similar upper and lower flanges of the adjacent section to 25 form upper and lower watertight reservoirs wholly within the radiator, and absorbent material moistened by fluid from the upper reservoir and located over the lower reservoir.
3. A combined radiator and humidifier 40 comprising a plurality of vertically arranged radiator sections, flanges on the sections uniting to form a humidifier chamber wholly within the radiator and located near the top thereof, absorbent material extending over the side of said chamber and hanging downwardly between the heating conduits of said radiator sections, and a reservoir supported by said sections for receiving drip from said absorbent material.
4. A combined radiator and humidifier 45 comprising a plurality of vertically arranged radiator sections, each section including three or more spaced heating conduits, a flange carried by an inner conduit and extending upwardly between the inner and the adjacent conduits, said flanges on adjacent sections uniting to form a water receiving chamber wholly within the radiator, a sheet of absorbent material having 50 one end within the chamber and the other end hanging downwardly outside the chamber and between the heating conduits of the radiator sections, and means supported by said sections for receiving drip from said absorbent material.
- 55 In witness whereof we hereunto subscribe our names this 6th day of February, 1918.
- FREDERICK LINDMEIER.
JUSTUS LINDMEIER.
